UNITED STATES PATENT OFFICE.

BENJAMIN F. LOCKWOOD, OF FREWSBURG, NEW YORK.

VALVE-FLOAT.

SPECIFICATION forming part of Letters Patent No. 726,317, dated April 28, 1903.

Application filed April 19, 1902. Serial No. 103,757. (No model.)

To all whom it may concern:

Be it known that I, BENJAMIN F. LOCKWOOD, a citizen of the United States, and a resident of Frewsburg, in the county of Chautauqua and State of New York, have invented 5 a new and useful Valve-Float, of which the following, in connection with the accompanying drawings, is a full, clear, and exact description.

10 My invention relates to floats for closing the valves of the supply-pipes of flush-tanks and similar vessels, and is an improvement on my valve-float as shown in a former Letters Patent, No. 659,819, dated October 16, 1900.

15 My present object is to construct a valve-float having an open chamber on its under side, in which the water is automatically held when the tank is emptied to weight the float and insure the operation of the inlet-valve.

20 The improvement consists in the use of a water seal instead of an air-operated valve for the air-vent tube.

A water seal is found to act evenly and positively, can be adjusted to balance the 25 amount of air and water in the float-bell to always float the same, can have the air-compartment of float partitioned off with metal, or the water will form its air-tight compartment by sealing the bottom of the float-bell, 30 and it is not subject to the objections which render an air-valve inoperative, as the accumulation of dust in the valve-seat.

In the drawings, Figure 1 is a sectional view of my improved valve-float in the tilted 35 position on the bottom of the emptied tank. Fig. 2 is a plan view of the lower side of the same, showing braces for the air-vent tube. Fig. 3 is a sectional view of float, showing closed air-chamber and modification of wa- 40 ter seal. Figs. 4 and 5 are sectional views showing further modifications of water seal.

Similar numerals refer to corresponding parts.

Numeral 10 is the main shell or float-bell, 45 which is usually made of sheet-copper or some non-corrodible material or in some suitable form in which the lower side may be left open. In some cases where I desire to have an unvarying amount of air to raise 50 the float I insert a second bell 11 within bell 10, which at once forms an air-tight cham-

ber 20 and at the same time leaves an open chamber on the under side of the float.

Numeral 12 is the air-vent tube extending down into the top of the bell 10 or connecting-bells 10 and 11. Bell 11 braces the lower end of tube 12, and when the bell 11 is not used the lower end of tube 12 is supported by braces 13. Tube 12 may be used for the air-vent tube; but I usually prefer to inclose the 60 adjustable tube 14 within tube 12, so as to regulate or rightly balance the air and water in the float-bell. At the lower end of tube 14 I place a water seal consisting usually of a bulb or chamber 15, lower end 16 of tube 14, 65 and hole 17 or 17'. At or near the upper end of tube 14 is air-vent 21 and disk or button 22, with which to adjust the seal.

23 is the valve-rod, and 24 the bottom, of the tank. 70

The water being admitted to the tank enters the lower side of bell 10 and rises to about dotted line 18, entering bulb 15 and tube 16 in sufficient quantity to give enough resistance to stop the exit of the air from chamber 75 19 and to float the bell and close the inlet-valve as the bell rises. Air-vent 21 serves both as an outlet and inlet for the air. When the water is let out of the tank, the water seal holds the water in the bottom of the float-bell until the float descends sufficiently to allow the water to run out through opening 17 and the air to enter. It is apparent that as soon as the float starts to descend it opens the inlet-valve and the purpose is accomplished. 80 85

Any form of a water seal which would hold the water in the lower part of the bell and seal the air in the upper part 19 would serve my purpose. The form shown in Fig. 3 is exactly the same as that shown in Fig. 1, 90 except as to the shape of part 15. The modifications shown in Figs. 4 and 5 would serve my purpose, though they are imperfect seals, since the weight of the water would prove insufficient to empty the seal through the narrowed 95 vent 17' until long after the float had descended and accomplished its purpose in opening the inlet-valve.

I claim as new—

1. A valve-float comprising a receptacle 100 open on its lower side, a vent-tube to said receptacle, and a water seal on said vent-tube.

2. A valve - float comprising a receptacle open on its lower side, a vent-tube adjustably supported in said receptacle that it may be raised and lowered therein, a water seal on said adjustable tube within said receptacle, and a suitable valve-rod attached to said receptacle.

3. A valve-float comprising the cup-shaped bell 10 open on its lower side, the tube 12 extending downward in bell 10 and having supports 13 for its lower end, a vent-tube 14 slidably mounted in tube 12 having air-vent 21

at its upper end, a water seal 15 17 at the lower end of said vent-tube, and a suitable valve-rod 23, substantially as and for the purpose specified.

In testimony whereof I have signed my name to this specification in the presence of two subscribing witnesses.

BENJAMIN F. LOCKWOOD.
